(57) **CLAIM**

The ornamental design for a utility bag with fasteners, as shown and described.

DESCRIPTION

FIG. 1 is a front elevational view of the utility bag with fasteners embodying my new design,

FIG. 2 is a rear elevational view thereof,

FIG. 3 is a right side view thereof,

FIG. 4 is a left side view thereof,

FIG. 5 is a top view thereof,

FIG. 6 is a bottom view thereof; and,

FIG. 7 is a front perspective view of the utility bag with fasteners, the attachable sleeve and utility belt shown in phantom comprising no part of the present invention.
